CAR SUPPORT

Donald S. Barrows, Rochester, N. Y., assignor to
The Symington-Gould Corporation, Rochester,
N. Y., a corporation of Maryland

Application September 17, 1940, Serial No. 357,178

8 Claims. (Cl. 248—351)

The invention relates to a support or stool and more particularly to a type thereof which is adapted to be associated with a railway vehicle. During the maintenance of railway vehicles it becomes necessary at times to raise the vehicle body from the supporting trucks for the purpose of repairing the trucks or car body as well as the equipment thereof. Repairs are most frequently made to the vehicle in shops equipped with overhead cranes so as to facilitate disconnecting the vehicle body from the supporting trucks. Since there is a limited number of cranes in each shop, it becomes necessary to provide subjacent supports for the vehicle body while the crane or cranes are being used elsewhere.

Another object, therefore, of the present invention is the provision of a support or stool capable of carrying a vehicle body while permitting the trucks to be run out from or in under the vehicle body.

Another object of the invention is to provide a support or stool for a vehicle body which is simple and durable in construction, of relatively few parts, and which may be easily handled.

To the attainment of the above and other objects of the invention which will become apparent from the succeeding description, reference is made to the accompanying drawings which illustrate forms of the invention and wherein:

Figure 1 is a partial end elevational view of a railway vehicle having a pair or plurality of supports or stools of the present invention associated therewith.

Figure 2 is a side elevational detailed view of a support or stool exemplary of the present invention, a portion thereof being shown in section.

Figure 3 is a front elevational view of the support or stool shown in Figure 2.

Figure 4 is a plan view of the support shown in Figures 2 and 3.

Figure 5 is a horizontal sectional view taken along the lines 5—5 of Figure 2, looking in the direction of the arrows, a portion thereof being shown diagrammatically to more clearly illustrate the construction.

Figure 6 is a horizontal sectional view taken along the line 6—6 of Figure 2, looking in the direction of the arrows.

Figure 7 is a partial plan view of a portion of a support removed therefrom to show the details of construction and corresponds to a view taken along the line 7—7 of Figure 2, looking in the direction of the arrows.

Figure 8 is a side elevational view of another embodiment of the present invention.

Figure 9 is a partial front elevational view and a partial vertical sectional view of the support or stool shown in Figure 8.

Figure 10 is a horizontal sectional view taken along the lines 10—10 of Figure 9, looking in the direction of the arrows.

Figure 11 is a horizontal sectional view taken along the lines 11—11 of Figure 9, looking in the direction of the arrows.

Figure 12 is a horizontal sectional view taken along the lines 12—12 of Figure 9, looking in the direction of the arrows.

Figure 13 is a sectional view taken along the lines 13—13 of Figure 12, looking in the direction of the arrows.

Referring now in detail to the drawings and particularly to Figures 1 to 7 thereof, wherein like reference characters indicate like parts, the numeral 1 designates, in a general manner, a support or stool embodying a form of the present invention and, as illustrated in Figure 1, is adapted to be placed in subjacent relation to a railway vehicle body 2, the latter of which is shown elevated from a railway truck 3. As will be noted by referring particularly to Figure 1, the railway truck 3 may be removed from beneath the vehicle body for the purpose of replacing the truck or body or placing another truck beneath the body, as desired, since a support or stool 1 is positioned adjacent each corner of the railway vehicle body.

The support or stool comprises a foundation, base or lower member 4 having a foot, bed or horizontal plate 5 adapted to bear upon the ground or floor 6 over an appreciable area. The foot plate is made circular or round so as to facilitate the support being tipped or inclined and then rolled into or out of vehicle body carrying position as well as for other purposes which will be hereinafter apparent. Upstanding from the foot plate and preferably cast integral therewith is a pair of substantially diametrically or longitudinally spaced end tubular members, protuberances, collars or housings 7 positioned adjacent what will be hereinafter termed the longitudinal center line of the base member, designated by the diagrammatic line A—A. The end tubular members are also positioned adjacent the periphery of the foot plate and have therebetween an intermediate tubular member, protuberance, collar or housing 8 upstanding from and formed integrally with the foot plate and located adjacent the periphery of the bed plate

on a line hereinafter referred to as the transverse center line of the base member, designated by the dot and dash line B—B. The end and intermediate collars or protuberances present a triangular formation offset with respect to the center of the foot plate for the purpose to be hereinafter explained.

Extending around the foot plate, adjacent the periphery thereof, is an arcuate upstanding beading or flange 9 which forms a reinforcement for the foot plate and merges into the collars or protuberances to present connections therebetween. Joining the end collars and the intermediate collar is a plurality of angularly disposed, preferably straight, ribs 10 in substantial alignment with the centers of the collars and converging toward the intermediate housing. The end tubular members are further connected by means of a straight longitudinal rib 11 which, like the ribs 10, upstands from and is integral with the foot plate. The longitudinal rib 11 is spaced a predetermined distance from the longitudinal center line A—A of the base to be substantially tangent to the end collars. Forming additional stiffening means for the bed plate are longitudinally spaced transversely directed auxiliary ribs 12 extending between the longitudinal ribs 11 and the adjacent portion of the peripheral flange 9. Since the flange and ribs present upwardly opening, cupped receptacles, which may accumulate water or dirt to deteriorate the base member, apertures 13 are interspersed among the thus formed receptacles to extend through the foot plate, and by reason of the apertures the weight of the base member is also reduced. From the foregoing it will be noted that a rugged foundation or base member has been constructed to withstand the strains to which it will be subjected in service.

Spaced a predetermined distance above the base member is a preferably cast upper, cap or seat member 14 having a horizontally disposed circular bearing plate 15 adapted to be positioned in subjacent relation or intimate contact with respect to a corner portion of the vehicle body. The upper surface 16 of the bearing plate is roughened, serrated or scored in any preferred manner, illustrative of which are the markings 17, and due to this arrangement a vehicle body gripping surface is provided on the cap to prevent relative movement between the support or stool and the vehicle body. Depending from the bearing plate and preferably formed integral therewith is a cluster of cylindrically formed tubular members, protuberances, collars or housings 18 communicating with one another to present, as viewed from the bottom in Figure 5, a clover leaf design and composed of end collars or protuberances 19 and an intermediate collar or protuberance 20. The cap housings are disposed substantially centrally of the bearing plate for the purpose to be hereinafter apparent. The collars or housings of the cap and base member are provided with bores or vertically disposed apertures 21 each of which has an axis thereof inclined with respect to the plane of its associated plate. The apertures 21 in the cap housings are in alignment with the apertures in the correspondingly positioned or related base member collars.

Extending between the cap and base member is a plurality of columns, standards, posts or shafts 22 composed of end posts 23 which extend into the apertures of the cap and base end collars and an intermediate column 24 which projects

into the apertures of the cap and base intermediate tubular members. The columns, which may be of any desired cross section and in the instant illustration are represented by pipes or tubes, are arranged so as to be capable of transmitting service forces from the cap to the base member and not interfere with the removal or replacement of a truck. Accordingly, the end columns are arranged substantially parallel to a vertical plane passing through the longitudinal center line A—A of the base member to afford ample clearance between the truck 3 and the support. Viewing the end columns from a different angle or from the front, as illustrated in Figure 3, they are inclined relative to a vertical plane passing through the transverse center line B—B of the base member. Preferably the end columns converge toward the cap 14, and by reason of this disposition they function as braces to prevent a longitudinal movement of the supported vehicle body.

The intermediate column is disposed substantially parallel to a vertical plane passing through the transverse center line B—B and angularly disposed to a vertical plane passing through the longitudinal center line A—A to permit the intermediate column to function as an anti-tipping means and reinforce the support against forces which may tend to shift the vehicle body in a transverse direction.

The columns are retained in position or secured to the cap by means of a substantially continuous weld 25 joining the upper extremities of the columns to the free extremities of the communicating housings 19 and 20. In a similar manner the columns are secured to the base member by individual continuous welds 26 located at the juncture of the columns and upper or free extremities of the base tubular members. As an added means of fastening the base and columns together, the foot plate is provided with orifices 27 extending therethrough and of lesser extent than the aligned or associated base housing apertures. These orifices permit entry to the interior of the columns for the introduction of a welding instrument as well as present shoulders 28 against which the lowermost extremities of the columns bear. Interior welds 29 are formed at the column-shoulder junctures to firmly secure the columns and base together. It is to be here noted that all exterior welds are formed with the cap, columns and base assembled and under a predetermined load, and by reason of this procedure the welds 25 and 26 are relieved of service strains to which they otherwise might have been subjected.

There is, positioned intermediate the height of the support or stool, a separator, brace, stiffener or spacer 30 interposed between the columns to prevent a buckling, spreading or collapsing action of the columns. The spacer, preferably of cast form, comprises intermittently spaced, cylindrically formed bearing walls 31 each having spaced abutments or pads 32 formed on extremities thereof and inclined to correspond with the inclination of the associated column. The pads 32, which are desirably the only portions of the spacer in intimate contact with the columns, are formed to ensure a bearing relationship between the spacer and all of the columns. The free extremities of the bearing walls are connected by means of webs 33 which are of arcuate formation in plan and of a height preferably less than the height of the bearing walls. The spacer is firmly secured to the columns by means of welds

34 positioned at the juncture of the upper and lower extremities of the bearing walls and columns.

Referring now to the embodiment of the invention of Figures 8 through 13, a stool or support for the same purpose as the previously described structure is designated by the reference character 1^a. As will be hereinafter apparent, the instant structure may also be arranged beneath a railway vehicle body so that the body can be retained in elevated position and the trucks thereof run out from therebeneath.

The support 1^a comprises, in part, a foundation, base or lower member 4^a having an annular, ring-like foot, bed or horizontal plate 5^a adapted to form a ground or floor contacting member. Associated with the bed plate and preferably cast integral therewith is an arcuate, convex or crown sheet or plate 35 joining the foot plate at the periphery thereof. The crown sheet is formed as illustrated so that the base member will be rugged and, as such, capable of withstanding the loads to which it will be subjected in service as well as present a spherical surface to permit water, brine or any impurities or foreign matter to fall therefrom. Projecting upwardly from the crown sheet is a plurality, preferably a pair, of longitudinally spaced end protuberances, collars, or housings 7^a positioned substantially diagonally of the foot plate and preferably adjacent a line A'-A', hereinafter referred to as the longitudinal center line of the foot plate or base member. Spaced a substantial equal distance from the end protuberances is an intermediate protuberance, collar or housing 8^a formed on a line B'-B', hereinafter referred to as the transverse center line of the foot plate. The intermediate housing or protuberance, like the end collars, is positioned adjacent the periphery of the crown sheet and presents a triangular formation therewith. It will be noted that the end and intermediate protuberances are offset with respect to the center of the base member, and for this reason a portion of the lower member may be positioned inwardly of horizontal clearance lines of a railway truck for the support of the body, while the remaining portion thereof, together with the hereinafter described parts of the stool, is well without the aforementioned clearance lines to facilitate the removal of the truck. Since, as will be hereinafter noted, the stresses pass to the base member through the protuberances, a plurality of ribs or gussets 10^a immediately underlie the protuberances and extend between the crown sheet and horizontal plate to form reinforcing members and thus rigidify the base member. A central aperture 13^a is formed in the crown sheet to lighten the foundation member.

Positioned at a predetermined distance above the base member is an upper cap or seat member 14^a comprising a horizontal bearing plate 15^a, circular in formation and adapted to be positioned in intimate contact with a car or vehicle body. The upper surface 16^a of the bearing plate is scored or serrated in any manner desired, such as the markings 17^a, so that the bearing plate may be provided with a car body gripping surface and thereby prevent relative movement between a car body and the support or stool.

Extending downwardly from the bearing plate and preferably formed integrally therewith is a plurality or group of collars, protuberances or housings 18^a forming a triangular design and comprising end protuberances 19^a and an intermediate collar 20^a. The cap protuberances are

symmetrically arranged or disposed centrally of the bearing plate for reasons to become herein-after apparent.

Extending between the cap and base member is 5 a plurality of columns, posts, standards or shafts 22^a comprising end posts 23^a, which bear against the end protuberances of the cap and base, and an intermediate column 24^a which is associated with the intermediate protuberances of the cap and base. The columns are illustrated as sections of pipe or tubular elements because this particular horizontal configuration is at present believed to be the best adaptable to the present construction. However, it will be clearly understood that standards of other horizontal contour may be employed with equal advantages. The end columns are arranged parallel to a vertical plane passing through the longitudinal center line A'-A' of the base member and inclined or sloping with respect to a vertical plane passing through the transverse center line B'-B' of the base member so that, thus disposed, they are positioned to overcome any longitudinal shifting movement of the car body relative to the stool or support. The intermediate column is parallel to a vertical plane passing through the transverse center line B'-B' and inclined relative to a vertical plane passing through the longitudinal center line A'-A' so that the intermediate shaft of the support will overcome any lateral shifting movement of the vehicle body. It will be noted that the lower extremities of the columns are spread apart an appreciable distance while the upper extremities thereof are in close proximity to one another to form an arrangement or disposition capable of withstanding the service stresses to which it will be subjected.

The columns or shafts are secured to the cap by means of suitably positioned welds 25^a joining the upper extremities of the columns to the cap protuberances and by welds 26^a connecting the lower extremities of the columns to the lower member protuberances. It is to be noted that, as in the previously described structure, the cap, columns and base member are associated and placed under a predetermined load, at which time the welds 25^a and 26^a are applied, and because of this procedure the welds will not be subjected to the load of a supported vehicle body.

A separator, brace, stiffener or spacer 30^a is 50 provided in the car stool intermediate its height to reinforce some of the columns. In the instant construction the stiffener, of cast form, merely extends between the end columns and desirably comprises horizontally spaced cylindrically formed bearing walls 31^a having arcuate concave surfaces 32^a thereof formed to correspond and adapted to be in intimate contact with the outer surfaces of the end columns. So as to present a full bearing relation between the walls 31^a and 55 end columns the arcuate surfaces 32^a are inclined substantially at an angle to correspond with the angle of inclination of the end columns. The bearing walls 31^a are joined or integrally united by means of a horizontal web 33^a. Welds 60 34^a are provided at the vertical limits of the bearing walls 31^a to secure the stiffener and end columns together.

Consideration has been given, in connection with the embodiment of the invention under immediate consideration, to the fact that the lower surface of the railway vehicle, adapted to be engaged by the cap surface 17^a, may be spaced at various distances above the ground in different types of cars. It might, therefore, become desirable to provide several stools of different height,

and while this may not be necessary, since the stools or supports may be made of a height to accommodate the highest car and accordingly accommodate the lowest type of car, provision has been made in the present embodiment so that the base member, cap and separator may be employed with stools of different height. Toward the accomplishment of the above, the protuberances are provided with spherical, convex, outwardly facing surfaces 36 against which the column extremities bear, and, as will be noted, the angle of inclination of the columns may be changed in stools of various heights and still preserve a full bearing relation between the cap and base member and the columns. Each protuberance is also provided with a substantially centrally disposed ring-like flange 37 which extends into the associated column or post extremities to form limiting means for the columns.

The surfaces 32^a of the separator are formed convexly when viewed from the front, as most clearly illustrated in Figure 13, so that the brace may be employed in stools of different heights and with posts irrespective of their angle of inclination.

It will be noted that various changes and alterations may be made to the illustrated and described construction without departing from within the spirit and scope of the appended claims.

I claim:

1. In a car support, the combination of a base comprising a foot plate, spaced tubular members upstanding from said foot plate, ribs joining said tubular members, a cap comprising a bearing plate, symmetrically arranged tubular members communicating with one another and downstanding from said bearing plate, columns angularly disposed relative to one another and having ends thereof extending into and secured to said tubular members, and a stiffener interposed between said columns intermediate the height thereof and secured thereto.
2. In a car support, the combination of a cast base comprising a foot plate having a pair of spaced tubular members upstanding from adjacent a center line thereof, another tubular member upstanding from said foot plate and spaced from said first named tubular members to present a triangular formation, ribs joining said tubular members, a cast cap comprising a bearing plate, symmetrically arranged tubular members communicating with one another and downstanding from said bearing plate, said downstanding tubular members being in alignment with said upstanding tubular members, and columns angularly disposed relative to one another extending into said tubular members and welded thereto.
3. In a car support, the combination of a cast base having integral spaced upstanding tubular members, a cast cap spaced vertically from said base and having integral communicating downstanding tubular members in alignment with said upstanding tubular members, standards extending between said base and cap and into said tubular members, welds securing said standards to said tubular members, a spacer means interposed between said standards intermediate the height thereof and secured thereto by welds, said spacer means comprising cylindrical seats

adapted to bear against said standards, and arcuate webs joining extremities of said cylindrical seats.

4. In a base for a car support, the combination of a foot plate, spaced tubular members upstanding from said foot plate adjacent the center line thereof, another tubular member spaced from said first named tubular members to present a triangular formation, substantially vertical ribs extending between and joining said tubular members, and a peripheral flange upstanding from said foot plate.

5. In a car support, the combination of a cast base having upstanding housings formed integral therewith, a cast cap spaced vertically from said base and having downstanding housings formed integral therewith, and a plurality of columns extending between said base and cap and projecting into said housings to be secured thereto, some of said columns being parallel to a longitudinal vertical plane and inclined with respect to a transverse vertical plane and another of said columns being parallel to said transverse vertical plane and inclined with respect to said longitudinal vertical plane.

6. In a car support, the combination of a cast base comprising a plate having a pair of spaced means upstanding from adjacent a center line thereof, another means upstanding from said plate adjacent another center line normal to said first named center line and spaced from said first named means to present a triangular formation, ribs formed integral with said means and plate, a cast cap comprising a bearing plate, symmetrically arranged means downstanding from said bearing plate, tubular shafts angularly disposed relative to one another extending between and associated with said means, welds securing said shafts to said means, and a cast spacer intermediate said base and cap extending between some of said shafts and welded thereto.

7. In a car support, the combination of a base comprising an arcuate sheet, triangularly arranged protuberances upstanding from said arcuate sheet, a cap comprising a bearing plate, symmetrically arranged protuberances downstanding from said bearing plate, convex surfaces on all of said protuberances, three tubular shafts angularly disposed relative to one another and bearing upon said convex surfaces, welds securing said shafts and protuberances together, and a spacer joining and welded to a pair of shafts.

8. In a car support, the combination of a base comprising an arcuate sheet, triangularly arranged protuberances upstanding from said arcuate sheet, a cap comprising a bearing plate, substantially symmetrically arranged protuberances downstanding from said bearing plate, convex surfaces on all of said protuberances, three tubular shafts bearing upon said convex surfaces, and welds securing said shafts and protuberances together; some of said shafts being parallel to a longitudinal vertical plane and inclined with respect to a transverse vertical plane, and another of said shafts being parallel to said transverse vertical plane and inclined with respect to said longitudinal vertical plane.

DONALD S. BARROWS.
